WASHING MACHINE

Edward R. De Luiz, Highland Park, Mich.

Application August 23, 1940, Serial No. 353,791

7 Claims. (CL 68—25)

This invention relates to washing machines of the type wherein the clothes to be washed are placed in a rotatable cylinder or the equivalent normally partially submerged in water and which cylinder, with the clothes contained therein, may be moved to a position above the water and turned at a relatively high speed to effect centrifugal drying of the clothes, the principal object being the provision of a washing machine of the type described that is simple in construction, economical to manufacture and efficient in operation.

Objects of the invention include the provision of a washing machine of the type described in which the washing cylinder or its equivalent is mounted for pivotal movement with respect to the co-operating tub and is arranged as a unit with driving mechanism therefor, the driving mechanism being so positioned and supported as to tend to counterbalance the weight of the washing cylinder and its contents; the provision of a washing machine of the type described including a tub and a bracket pivotally mounted thereon, the bracket rotatably supporting a shaft and the shaft in turn supporting the washing cylinder normally within the tub, the bracket also supporting a motor and means for connecting the motor to the shaft, whereby the bracket, shaft, washing cylinder, motor and driving means forms a unit pivotable about the pivotal axis of the bracket without disturbing the driving relation of the various parts; the provision of a washing machine of the type described in which the driving mechanism includes a speed change mechanism; the provision of a washer of the type described including an imperforate member surrounding the washing cylinder in generally spaced relation with respect thereto and movable bodily with the washing cylinder in its pivotable movement about the axis of the aforementioned bracket; the provision of a construction as above described in which the guard is provided with an open corner whereby when the washing cylinder is swung to a vertical position for wringing purposes the water discharged from the clothes in the cylinder is directed back into the tub; the provision of a construction as above described in which the shaft which supports the washing cylinder projects through one end wall of the tub and such end wall is cut away to permit swinging movement of the shaft therethrough, the guard for the washing cylinder including an end wall co-operating with the cut-away portion of the end wall of the tub to seal the same against loss of water during washing operations; the pro-

5 vision of a construction as above described in which the guard includes a side pivotally secured thereto and co-operating with the top edge of the tub when the washing cylinder is in its normal washing position to close the top of the tub; the provision of a construction as above described in which the washing cylinder is provided with an open end to permit reception and discharge of clothes therethrough, together with a closure for 10 the open end of the washing cylinder mounted on the guard and movable to and from operative relationship with respect to the open end of the washing cylinder; the provision of a construction as above described in which the positioning 15 of the closure for the open end of the washing cylinder is a condition precedent to placing the washing cylinder in a position for normal washing movement; the provision of a novel drive structure for the washing cylinder permitting 20 the same to be driven at different rates of rotation for washing and wringing purposes; and the provision of a novel drive mechanism including speed change mechanism in the drive to the washing cylinder operated automatically as the 25 washing cylinder is moved between horizontal and vertical positions to drive the cylinder at low or high speeds.

The above being among the objects of the present invention the same consists in certain novel 30 features of construction and combinations of parts to be hereinafter described with reference to the accompanying drawings, and then claimed, having the above and other objects in view.

In the accompanying drawings which illustrate 35 a suitable embodiment of the present invention and in which like numerals refer to like parts throughout the several different views,

Fig. 1 is a vertical sectional view through a 40 washing machine constructed in accordance with the present invention and taken axially of the washing cylinder thereof, the washing cylinder and driving mechanism being illustrated in solid lines in the position which they assume for normal washing operations and in dotted lines in the 45 position which they assume for wringing operations;

Fig. 2 is an enlarged transverse sectional view taken on the line 2—2 of Fig. 1;

Fig. 3 is an enlarged transverse sectional view taken on the line 3—3 of Fig. 1;

Fig. 4 is an enlarged transverse sectional view taken on the line 4—4 of Fig. 1;

Fig. 5 is an enlarged transverse sectional view taken on the line 5—5 of Fig. 1 and illustrating in

greater detail the construction of the speed change mechanism therefor; and,

Fig. 6 is an enlarged fragmentary transverse sectional view taken on the line 6-6 of Fig. 1 and illustrating the latch mechanism for holding the washing cylinder in vertical position during a wringing operation.

Referring to the accompanying drawings it will be noted that the washing machine includes a tub indicated generally at 10 of more or less U-shape in transverse cross-section, having a front end wall 12 and a rear end wall 14. The tub is supported from the floor by means of a leg structure including a sheet metal skirt 16 which surrounds the tub and is secured to the opposite side thereof along a line slightly below its center. The skirt 16 at the front end of the tub is arranged in flush relationship with respect to the forward end 12 but at the rear end it extends rearwardly of the rear wall 14 and is provided with tapered side extensions 18 lying generally in the plane of the outer sides of the tub and provided with inwardly turned marginal flanges 20, best shown in Fig. 4, for stiffening purposes. Feet 22 are formed at the four corners of the skirt 16 adjacent the lower edge thereof, the legs 22 serving to fixedly support the tub 10 from a floor and preferably being provided with knobs, rollers, casters or the like 24 permitting the tub to be moved from place to place upon a floor. Adjacent its forward end the tub 10 is provided with a drain valve 26 in its bottom for the purpose of permitting the liquid contents of the tub to be drained therefrom in a conventional manner.

As best illustrated in Figs. 1 and 4 a relatively heavy bracket 30 is suitably fixed as by riveting, welding, brazing, soldering or the like to the outer face of the rear wall 14 of the tub 10, the bracket extending substantially the full width across such rear face and having a marginal forwardly turned flange portion 32 embracing the adjacent margin of the side and bottom walls of the tub 10, the bracket thus being rigidly and immovably secured to the tub. The bracket 30 is provided adjacent its upper edge with a pair of transversely spaced rearwardly projecting bosses 34 between which the eye 36 of a second bracket 38 is pivotally secured by means of a pin 40. The bracket 38 rotatably supports therein a shaft 42 disposed with its axis in a plane perpendicular to the axis of the pin 40 and normally lying in a horizontal plane as illustrated in Fig. 1. The shaft 42 projects to a point interiorly of the tub 10 and, for the purpose of permitting such projecting end of the shaft 42 as well as parts to be hereinafter described and carried by the shaft 42 to be moved therethrough, the rear wall 14 of the tub is cut away as best indicated at 44 in Fig. 4 along a horizontal line approximately horizontally aligned with the axis of the pin 40.

Within the tub 10 the shaft 42 has fixed thereto as by means of a spline connection and nut 46 a flanged hub 48 to which a washing or agitating element is secured. While in the broader aspects of the present invention the washing element or agitator may be of any suitable or conventional form, it is preferably, and is so shown by way of illustration, in the form of a perforate washing cylinder 50 the righthand end wall 52 thereof, as viewed in Fig. 1, is rigidly fixed to the flange of the hub 48. The opposite end of the washing cylinder 50 is inwardly flanged as at 54 a short distance so as to leave a circular opening therein through which clothes may be introduced into the interior of the washing cylinder 50 and removed

therefrom. The washing cylinder 50 is preferably provided interiorly thereof with a plurality of transverse vanes or bars 56 for the purpose of enabling greater agitation of the clothes during rotation of the cylinder 50 as will be readily understood by those skilled in the art.

The rear end of the bracket 38 is peripherally enlarged to form an annular flange 60 which serves as a closure for the open end of, and to support, a housing or casing 62 fixed thereto. The housing 62 encloses a second housing comprising a cup-shaped member 64 fixed against relative rotation to the righthand end of the shaft 42, and a cover portion 66 provided with a hub which is journaled in the housing member 62 centrally thereof. The cover member 66 rotatably supports centrally thereof a shaft 68, independent of the shaft 42, and which projects outwardly to the right, as viewed in Fig. 1, and there carries a driving pulley 70. As best brought out in Figs. 1 and 5 the shaft 68 has fixed to its inner end within the casing 64-66 an eccentric 72, and rotatably mounted upon the eccentric 72 is a spur gear 74. The inner face of the housing member 64 is formed to provide an internal gear 76 which lies in mesh with the spur gear 74. The above described arrangement forms a conventional form of gear reduction mechanism the reduction ratio of which is equal to the difference in number of teeth between the internal and the external gear divided by the number of teeth on the driving gear. In the present case it is assumed that the gear 74 will have twenty teeth and the gear 76 twenty-two teeth, giving a reduction ratio of one to ten.

In order to render the above described reduction gear mechanism inoperative when it is desired to drive the shaft 42 at the same speed as the shaft 68 the following mechanism is provided. The hub of the member 66 projects to the right past the end of the housing member 62 and such projecting end is axially notched as at 80 in Fig. 1. A peripherally grooved sliding dog clutch member 82 is axially slidably but relatively non-rotatably mounted upon the righthand end of the shaft 68 and is provided with teeth 84 which are engageable with the notches 80 in the member 66 when the dog member is moved to the left, as viewed in Fig. 1. When the dog clutch member 82 is in the position indicated with the teeth 84 out of engagement with the notches 80, the shaft 68 may turn relatively to the housing 64-66 and consequently the reduction gear mechanism is operative. However, if the dog clutch member 82 is shifted to the left to bring the teeth 84 into engagement with the notches 80, then the shaft 68 and housing 64-66 are locked together for equal rotation. Consequently in the latter position of these parts the shafts 68 and 42 are locked together for equal rotation and the washing cylinder 50 will rotate at the same speed as the shaft 68.

In order to control the position of the dog clutch member 82 a lever 86 is pivotally mounted at 88 on an extension of the bracket 38 and its central portion is bifurcated and straddles the dog clutch member 82 and is provided with diametrically opposed pins loosely received in the peripheral groove therein in accordance with conventional practice. The lever 86 projects downwardly below the clutch member 82 and is there pivotally connected to one end of a rigid link 90 the opposite end of which is pivoted at 92 to one of the eyes 34 of the bracket 30 at a point spaced upwardly from the axis of the pin

40. The pivot point 83' is so arranged that the teeth of the dog clutch member 82 are out of engagement with the notches 80 when the cylinder 50 is in horizontal position, but are automatically brought into engagement therewith when the cylinder 50 is moved to vertical position. This is not only a convenience but also a safety feature as it prevents the cylinder 50 from being turned at high speed when partially submerged in the water in the tub.

In order to drive the shaft 68 an electric motor 90 is mounted upon a suitable bracket 92 formed integrally with the bracket 38 and is provided with a driving pulley 94 connected by a belt 96 with the pulley 70. The pulleys 94 and 70 afford an additional means whereby a further reduction in the drive between the motor 90 and the shaft 42 may be obtained if desired. It will be understood that the speed of rotation of the shaft 42 both in normal washing operation and wringing operation may vary upon the size of the cylinder 50 and the desires of the individual designer. In the smaller sizes of washers adapted for the needs of the average small family, it will ordinarily be desirable to turn the washing cylinder 50 approximately 80 R. P. M. during washing operations and 800 R. P. M. during wringing operations. Thus where the electric motor 90 is of the conventional type turning 1780 R. P. M. per minute the ratio between the pulleys 70 and 94 will preferably be a little more than 2 to 1 where a gear reduction mechanism of the ratio described is used in conjunction therewith.

With the construction thus far described it will be understood that the bracket 28, which is pivoted at 40, carries the washing cylinder 50, the gear reduction mechanism described and the electric motor 90 and consequently all of these parts may be pivoted as a unit about the axis of the shaft 40. The bracket 30 preferably cooperates with the bracket 38 in such a manner that when the parts are swung to the position indicated in full lines in Fig. 1, that is when the bracket 38 is moved in a counterclockwise direction of rotation as viewed in Fig. 1, downward movement of the bracket and parts supported thereby will be limited to a position in which the washing cylinder 50 is positioned with its axis substantially horizontal as indicated. In such position of the parts it will be apparent from an inspection of Fig. 1 that the weight of the motor 90 and the gear reduction mechanism and driving means therefor are located primarily to the right of a vertical plane including the axis of the pivot pin 40 and consequently serve to counterbalance to a greater or lesser extent the weight of the washing cylinder 50 and any contents thereof. When this unit is swung to bring the axis of the washing cylinder into a vertical position, as illustrated in dotted lines in Fig. 1, it will be understood that because of the fact the axis of the pivot pin 40 is below the axis of the shaft 42, when the unit is swung to vertical position the bulk of the weight will be to the right of the pivot pin 40 and consequently will tend to maintain the unit in vertical position. Contact of the flange 60 with the bracket 30 may be employed to limit movement of the unit about the shaft 40 in a clockwise direction as viewed in Fig. 1. Additionally, it may be desirable, under certain conditions at least, to provide means for latching the unit in vertical position and in Fig. 6 one means for effecting this result is shown. This comprises a spring arm 200 fixed to the bracket 30 and extending per-

pendicularly outwardly therefrom, the free end being formed to provide an inwardly extending projection 202 adapted to resiliently co-operate with a notch, such as 204, in the flange 60 of the bracket 38 when the unit is swung to vertical position. The arm 200 being formed of spring material, the end 202 will automatically drop into the notch 204 when brought into matching relation therewith, and when it is desired to return the unit to normal horizontal position, a firm pull on the unit will cause disengagement of the arm 200 and notch 204 to permit such movement.

It will be appreciated from the above description that in operation, when it is desired to wash some clothes or other articles, the washing cylinder 50 is swung upwardly sufficient to permit the introduction of such articles into the hollow interior thereof and it is then returned to the horizontal position indicated in full lines in Fig. 1, the dog clutch 82 being withdrawn from interengaging relation with respect to the notches 80 of the part 68. Soapy water is introduced into the lower part of the tub 10 but to a point below the upper edge of the cut-away portion 44 of the rear wall 14 of the tub. The motor 90 is then energized to cause it to drive the shaft 68, and the shaft 68 through the gear reduction mechanism described drives the shaft 42 and consequently rotates the washing cylinder 50. The perforations in the cylinder 50 permit ready flow of the water into and out of the washing cylinder and the bars 56 constantly turn the articles through the water and agitate them therein in order to effect the desired cleansing thereof. When the washing of the articles is completed, then either one of two different steps may be followed. The first of these would be when the articles in the washing cylinder 50 constitute the entire wash, in which case the soapy water may be drained through the valve 26 and replaced by rinse water, whereupon further rotation of the washing cylinder may be effected to thoroughly rinse the articles. After the rinsing operation or in event there are more articles to be washed in the soapy water, the cylinder 50 is swung up into vertical position, the dog clutch member 82 being moved to lock out the gear reduction mechanism by such movement, and the cylinder 50 is then whirled at a relatively high speed to centrifugally discharge the water from the articles. Where it is the soapy water that is thus discharged from the articles being washed, they may be removed from the cylinder and accumulated until the entire washing is completed in the soapy water, after which the soapy water may be withdrawn from the tub and replaced by rinse water and all the articles then replaced in the washing cylinder 50 in desired sized lots to effect a rinsing thereof, followed by the centrifugal drying step. In either event it will be understood that when the cylinder 50 is moved from horizontal to vertical position it is not necessary to lift the water in the tub with the cylinder, as the only water which requires lifting will be that absorbed by the clothes, the remainder simply running out of the cylinder and staying in the tub. Furthermore, during such movement of the cylinder, the clothes therein will tend to fall to the bottom end of the cylinder 50, thus lessening the amount of work required by the housewife in raising the cylinder and increasing the counterbalancing effect of the motor and drive.

It will, of course, be understood that with the construction thus far described, during the cen-

trifugal drying process the water would be discharged from the washing cylinder 50 without restraint and very little if any would be returned to the tub. In order to prevent this, as well as to provide certain other advantages in the construction described the mechanism includes the following additional parts. An imperforate sheet metal guard member 100 of substantially the same general cross-sectional conformation as the tub 10 is positioned within the tub 10 and in surrounding relationship with respect to the cylinder 50, it being of substantially although slightly greater length than the washing cylinder 50. The guard 100 at its upper edge is provided with an outwardly turned marginal flange 102 which overlies and which rests upon the upper outwardly flanged marginal edge of the tub 10 when in normal position for a washing operation. The guard 100 is open at its lefthand end as viewed in Fig. 1, but is provided with a rear or right-hand end wall 104 formed integrally therewith and which extends to the top thereof. This rear wall 104 is suitably fixed in water tight relation to the flange 106 on the bracket 38 and when the washing cylinder 50 is in its normal horizontal washing position such rear wall 104 bears against the inner face of the rear wall 14 of the tub 10 and provides a water seal at this point to prevent escape of water over the upper edge of the cut-away portion 44 of such rear wall 14. At its rear edge the wall 14 is provided at its opposite sides with an outwardly directed flange 108 and the tub 10 at each of its opposite sides is provided with an inwardly projecting co-operating flange 110, lying to the left of the flange 108 as viewed in Fig. 1, and in a position so that the co-operating flange 108 will bear against it when the cylinder 50 is in its normal horizontal washing position to provide a water seal along the sides of the tub. The flanges 108 extend downwardly to a point lying approximately in a horizontal plane including the axis of the pivot pin 40, so that there will be no interference between the flanges 108 and 110 when the washing cylinder 50 is swung upwardly into vertical position.

The upper side of the guard 100, when in horizontal position, is closed by a cover member 112 pivotally secured to the rear wall 104 thereof. The cover 112 which, of course, is imperforate, co-operates with the flange 102 around the upper edge of the guard 100 and with the upper edge of the tub 10 to also provide a closure for the tub 10 when the mechanism is in its normal washing position. A handle 114 is preferably provided to aid in manipulating the cover 112.

The guard 100 adjacent its lower righthand end as viewed in Fig. 1 is cut away as indicated at 116 in Figs. 1 and 3 to provide an opening of relatively large size therein. When the tub is swung up into vertical position the opening 116 is vertically within the opposite end walls of the tub 10 and materially below the upper edge of the tub 10. The guard 100 and its cover 112 being imperforate, all water which is discharged from the washing cylinder 50 during a centrifugal wringing process is caught by the guard and its cover and drained downwardly by gravity therein and discharges through the opening 116 back into the tub 10.

In order to close the open lefthand end of the cylinder 50, as viewed in Fig. 1, during a washing operation, the following mechanism is provided. A strap-like member 120 is pivoted at 122 at one end to the open end of the guard 100 at

the lower forward edge thereof as indicated in Fig. 1. The strap 120 extends outwardly and then upwardly from its pivot point 122 and its upper end is bent outwardly as at 124 so as to overlie the upper edge of the forward wall 12 of the tub 10. A circular closure member 126 is supported by posts 128 from the strap 120 in a position to close the open end of the cylinder 50. The size of the closure 126 and the length of the posts 128 are preferably such that the closure 126 is positioned with its periphery in relatively close but spaced relation with respect to the inner margins of the end wall 54 of the cylinder 50, so as to provide an effective closure for such open end of the washing cylinder but without setting up any rubbing friction. A handle 130 is preferably provided on the strap 120 to facilitate its manipulation with the cover 112.

It will be observed that because of the relation of the strap 120 with respect to the guard 100 and front wall 12 of the tub 10 it is necessary for the strap 120 and closure 126 to be in their normal operative positions before the washing cylinder 50 is placed in its normal washing position. When it is desired to introduce or remove clothes from the open end of the washing cylinder 50, the latter must be raised sufficiently to permit the strap 120 and its closure member 126 to be swung outwardly away from the open end of the washing cylinder 50. It might be noted at this point that the cover 112 for the guard 100 may be lifted away from the guard 100 while the washing cylinder 50 is in its horizontal position, this permitting the introduction of fresh water or the like into the tub 10 without necessitating moving the washing cylinder 50 to its vertical position.

It will be appreciated from the above description that with the exception of the various brackets, speed reducing mechanism, driving motor, etc., the construction of the washer of the present invention is such as to permit it to be fabricated substantially entirely from sheet metal, thus enabling it to be built at a minimum of cost. It will also be appreciated that the construction is unusually convenient for a housewife inasmuch as the clothes may be washed and wrung without necessitating their removal from the washing cylinder 50 and that because of the relative positioning of the driving and reduction mechanism with respect to the pivotal axis of the unit of which these elements are a part, the weight of the washing cylinder 50 and its contents is sufficiently counterbalanced to permit the washing cylinder to be swung from horizontal to vertical position and from vertical to horizontal position with a minimum of effort. An additional feature is that because of the guard 100, the wash water between the guard 100 and the bottom of the tub 10 will be in a more or less quiescent state and will serve to trap dirt, lint and other materials washed out of the clothes and prevent their ready return to the bulk of the wash water between the guard 100 and the washing cylinder 50 and in the washing cylinder 50. At the same time the wash water in the tub is capable of freely flowing through the ends of the guard 100 so as to obtain a desired circulation of the water in the washer.

Formal changes may be made in the specific embodiment of the invention described without departing from the spirit and substance of the broad invention, the scope of which is commensurate with the appended claims.

What is claimed is:

1. In a washing machine, in combination, a tub

having an open top, means for supporting said tub in fixed relation with respect to a supporting surface, a bracket pivotally mounted about an axis fixed with respect to said tub for movement about a horizontal line, a shaft rotatably mounted in said bracket with the axis thereof arranged in a plane perpendicular to the pivotal axis of said bracket, a perforate washing cylinder fixed to an end of said shaft for rotation therewith and normally positioned within said tub, the end of said cylinder opposite said shaft being open, means supported by said bracket exteriorly of said tub and movable therewith for driving said shaft, an imperforate water guard surrounding said cylinder in spaced relation thereto and fixed to said bracket for movement therewith, said water guard including a part pivotally attached thereto co-operating with the open top of said tub to close the same, and a closure for the open end of said cylinder pivotally mounted on said guard and movable bodily therewith, the construction and arrangement being such that said cylinder and guard may be moved from a position within said tub to a position in which said cylinder is arranged with its axis vertical and principally positioned exteriorly of said tub.

2. In a washing machine, in combination, a tub having an open top, means for supporting said tub in fixed relation with respect to a floor, a bracket mounted for pivotal movement about a horizontal axis fixed with respect to said tub, a shaft rotatably mounted in said bracket and positioned with its axis in a plane perpendicular to the pivotal axis of said bracket, said shaft projecting through the rear end of said tub and the rear wall of said tub being cut away to permit swinging movement of said shaft with said bracket, a perforate washing cylinder fixed coaxially to the end of said shaft and normally lying with its axis horizontal and within said tub, means exteriorly of said tub and supported by said bracket for driving said shaft and cylinder, and an imperforate water guard fixed to said bracket in surrounding and spaced relation with respect to the periphery of said cylinder and including an end wall portion co-operating with the end wall of said tub to seal said cut-away portion thereof against loss of water from said tub, said guard also including a part pivotally associated therewith and co-operating with the upper edges of said tub to form a closure therefor, said bracket, cylinder, driving means and guard forming a unit pivotable about the pivotal axis of said bracket enabling said cylinder to be optionally located in said tub for washing purposes or located substantially exteriorly of said tub with its axis vertical for centrifuging purposes.

3. In a washing machine, in combination, a tub having an open top, means for supporting said tub in fixed relation with respect to a floor, a bracket mounted for pivotal movement about a horizontal axis fixed with respect to said tub, a shaft rotatably mounted in said bracket and positioned with its axis in a plane perpendicular to the pivotal axis of said bracket, said shaft projecting through the rear end of said tub and the rear wall of said tub being cut away to permit swinging movement of said shaft and parts carried thereby with said bracket, a perforate washing cylinder fixed co-axially to the end of said shaft and normally lying with its axis horizontal and within said tub, means including a speed change mechanism supported by said bracket exteriorly of said tub for driving said shaft and cylinder, and an imperforate water guard fixed

to said bracket in surrounding and spaced relation with respect to the periphery of said cylinder and including an end wall portion co-operating with the end of said tub to seal said cut-away portion thereof against loss of water from said tub, said guard also including a part pivotally associated therewith and co-operating with the upper edges of said tub to form a closure therefor, said bracket, cylinder, driving means and guard forming a unit pivotable about the pivotal axis of said bracket enabling said cylinder to be optionally located in said tub for washing purposes or located substantially exteriorly of said tub with its axis vertical for centrifuging purposes.

4. In a washing machine, in combination, a tub adapted to be supported in relatively fixed relation with respect to a floor and having an open top, a bracket pivotally mounted with respect to said tub, a shaft rotatably mounted in said bracket with its axis arranged in a plane perpendicular to the pivotal axis of said bracket, a perforate washing cylinder fixed with respect to an end of said shaft and normally positioned within said tub, a sheet metal water guard surrounding the periphery of said cylinder in spaced relation thereto, and a closure for one end of said cylinder pivotally supported by said guard, said cylinder and guard being swingable with said bracket from a position in which it is located substantially within said tub and with its axis horizontal to a position in which it is substantially exterior of said tub and with its axis vertical, the construction and arrangement of said closure being such as to require it to be operatively positioned with respect to said open end of said cylinder when said cylinder is positioned in its normal operative position with said tub.

5. In a washing machine, in combination, a tub adapted to be supported in relatively fixed relation with respect to a floor and having an open top, a bracket pivotally mounted with respect to said tub, a shaft rotatably mounted in said bracket with its axis arranged in a plane perpendicular to the pivotal axis of said bracket, a perforate washing cylinder fixed with respect to an end of said shaft and normally positioned within said tub, a sheet metal water guard surrounding the periphery of said cylinder in spaced relation thereto, said water guard comprising a U-sectioned imperforate member fixed to said bracket and movable bodily therewith, a closure for the open side of said guard co-operating with the upper edge of said tub to form a closure therefor, an end wall on said guard co-operating with the corresponding end of said tub to seal the same against leakage, and the lower portion of said guard adjacent that end of said cylinder which is fixed to said shaft having an opening therein whereby when said cylinder and guard are swung to a substantially vertical position water discharged from said cylinder will be confined by said guard and caused to be discharged back into said tub.

6. In a washing machine, in combination, a tub adapted to be supported in fixed relation with respect to a floor, a washing cylinder normally arranged within said tub with its axis in horizontal relation therein, means pivotally supporting said washing cylinder on said tub at one end thereof whereby said washing cylinder may be swung from a horizontal position to a vertical position, a motor, driving means between said motor and said washing cylinder including a speed change mechanism having an element shiftable between high and low speed positions,

and means operative during swinging of said washing cylinder between horizontal and vertical positions automatically operable to shift said shiftable element from one speed position thereof to another speed position thereof, the last mentioned means positively preventing the placing of said speed change mechanism in its high speed position when said washing cylinder is in horizontal position.

7. In a washing machine, in combination, a tub adapted to be supported in fixed relation with respect to a floor, a washing cylinder arranged in horizontal position within said tub, means for supporting said washing cylinder about a pivotal axis at one end of said tub whereby said cylinder may be swung from its normally horizontal po-

sition to a position in which its axis is vertically arranged, a driving motor for said washing cylinder mounted for bodily swingable movement therewith about said pivotal axis, a speed change mechanism including a shiftable element providing a driving connection between said motor and said washing cylinder, and means including a link pivotally mounted at one end thereof at a point fixed with respect to said tub and spaced 5 from said pivotal axis of said cylinder and having its opposite end operatively interconnected with said shiftable element, said link being operable during swinging movement of said cylinder to shift said shiftable element between different 10 speed positions of said speed change mechanism.

EDWARD R. DE LUIZ.
